UNITED STATES PATENT OFFICE.

JOHN C. GLEASON, OF WHITE CASTLE, LOUISIANA.

DESIGN FOR A WATCHCASE.

47,691.

Specification for Design. Patented Aug. 10, 1915.

Application filed March 27, 1915. Serial No. 17,542. Term of patent 3½ years.

To all whom it may concern:

Be it known that I, JOHN C. GLEASON, a citizen of the United States, residing at White Castle, in the parish of Iberville and State of Louisiana, have invented a new, original, and ornamental Design for Watchcases, of which the following is a specification, reference being had to the accompanying drawing, forming part thereof.

The figure is a plan view of the watch case, showing my new design.

I claim:

The ornamental design for a watch case as shown.

JOHN C. GLEASON.

Witnesses:

JOS. RYBISKI,
LOUIS A. RYBISKI.
